UNITED STATES PATENT OFFICE.

WILLIAM A. HILLER, OF MANOR, TEXAS, ASSIGNOR TO THE MURRAY COMPANY, OF DALLAS, TEXAS, A CORPORATION OF TEXAS.

FEEDER FOR COTTON GINS.

Application filed April 7, 1922. Serial No. 550,279.

To all whom it may concern:

Be it known that I, WILLIAM A. HILLER, a citizen of the United States, residing at Manor, in the county of Travis and State of Texas, have invented certain new and useful Improvements in Feeders for Cotton Gins, of which the following is a specification.

My invention is an improvement in feeders for cotton gins.

It has been common before feeding seed-cotton to the gin, to give the seed-cotton a preliminary treatment, designed to remove as much as possible of the sand, trash, etc., which is commonly mixed with the seed-cotton as it comes to the ginnery. This has been accomplished by passing the seed-cotton through a feeder-cleaner, which consists essentially of a rotating drum, having spikes arranged about and along its periphery, which drum rotates within a curved screen suitably encased. The spikes drag and beat the seed-cotton against the inside of the screen, the dirt and trash dropping through the screen to the bottom of the casing, from which it is removed in any manner desired, usually by a screw conveyor. The seed-cotton is carried over the screen surface and ejected into the hopper of the gin, or to a conveyor which carries the cleaned cotton to the gin.

In the drawings:

Figure 1 is a cross-section of my improved attachment;

Figure 2 is a longitudinal section on line 2-2 of Figure 1; and

Figure 3 is an end view of a part of a gin and a feeder-cleaner with my attachment, showing the relations of the parts.

In the old feeder-cleaner the seed-cotton enters the feeder-cleaner from a source of supply, at the opening, *a*, at the top of the casing *E*. The seed cotton is passed between the rollers *a'*, *a'*, turning as indicated by the arrows in Figure 1, and is compressed and formed into a loose bat, which, as it descends, is received by the beater drum *D*, and carried around by the spikes, *d*, as indicated.

There are many conditions of the seed-cotton which make it desirable to give different amounts of cleaning treatment. Seed-cotton which is fairly clean on receipt does not require the treatment that is nec-

essary when it is full of sand and trash; unnecessary treatment is to be avoided as it is not in itself beneficial. When ginning green, immature or damp seed-cotton, it is also desirable to avoid machining the cotton more than is necessary.

In most cleaner-feeders as heretofore constructed there has been a lack of possibility of variation of treatment to meet varying conditions. A beater drum and encasing screen of a fixed size has been employed and this size has been designed on an average basis to handle all kinds of seed-cotton, with the result that there was an undesirable amount of machining of some seed-cotton and an insufficient amount for other seed-cotton.

It is the object of my present invention to improve upon prior devices of the kind by providing means for giving more or less cleaning treatment to seed cotton, as may be indicated by the condition of the cotton and also to provide an attachment or auxiliary which may be applied to and combined with, existing machines to achieve this end and which may be used or not at the judgment of the operator.

In my new device I employ an auxiliary drum 1, properly mounted within a screen, 2, enclosed in a casing, 3. The drum 1 is mounted upon a shaft 11 carried in bearings 12 in casing 3. As shown, the auxiliary casing and screen is made up, on the upper side, of the section *e'* *E'* which may form part of the regular feeder-cleaner. This section *e'*, and its section *E'* is hinged at *e''* to the regular cleaner feeder and when it is desired to apply the auxiliary cleaner, section *E'*, *e'*, is swung up, leaving an opening in the side of the casing of the regular cleaner, and so as to form the upper side of the screen and casing of the auxiliary cleaner. It is obvious of course that this is especially useful when the new cleaner is to be used in connection with a cleaner-feeder having a hinged rear section, as is very common. In other cases the new cleaner is provided with a screen-casing to the point *e''* and a suitable opening in the casing of the feeder-cleaner is made, against which the opening in the auxiliary cleaner is set.

The shaft *d'* of the feeder-cleaner and the shaft 11 of the auxiliary cleaner are each

provided with pulleys or the like, outside the casing, and the auxiliary cleaner is run by a belt *h* or other connection from the feeder-cleaner (see Figure 3).

5 The mode of operation is as follows: Seed-cotton being passed into the feeder-cleaner at, *a*, usually from an elevator chute under which the feeder-cleaner is disposed, the seed-cotton is engaged by the rollers, *a'*, *a'*, and somewhat compressed and formed into a soft bat. The bat is received by the drum, *D*, turning as indicated by the arrow, Figure 1, and moved by spikes *d* against the drum 1, rotating as indicated, by the spikes 10 *d* on which the seed cotton is carried around against the screens *e'*, 2, the dirt and trash 15 passing the screens and lodging finally in the screw conveyor *C*. The cotton is urged over screen 2 and finally is again taken by drum *D* and urged along screen, *e*, to the opening *f*, of the chute, *g*, through which it passes to the gin *F*. When less machining of the seed cotton is desired, the auxiliary 20 cleaner may be separated from the cleaner 25 feeder by replacing section *E'* *e'*, when the cleaner feeder will operate in the ordinary way. When it is desired to give the minimum cleaning action, the belt, *h*, or other 30 driving means from the drum *D* to drum 1 may be disconnected when the drum *D* will deliver the seed-cotton direct to the opening

f, of the chute *g*, passing the seed-cotton over the screen *e*, only.

I claim:

1. An auxiliary cleaner consisting of a rotatable beater drum; a screen and casing, coincidentally partially surrounding the drum, the casing and screen having one coincident opening to one side of the drum; means to connect the casing at the opening, 35 to an opening in the casing of a gin feeder.

2. An auxiliary cleaner, consisting of a rotatable beater drum; a screen and casing, coincidentally partially surrounding the drum; the casing and screen having one coincident opening to one side of the drum, 40 applicable to an opening in the casing of a 45 gin feeder.

3. In a gin feeder-cleaner, a pair of feeder rolls in the upper end of the casing; a rotating feeder-cleaner drum beneath the feed rolls to receive the cotton fed by the feed rolls; a rotatable cleaner drum parallel with and to one side of the feeder-cleaner drum; 50 a screened casing surrounding both drums, except for an upper inlet to the feed rolls and an exit opening to the gin, adjacent and to one side of the feeder-cleaner drum.

Signed at Manor, Texas, this 30th day of March, 1922.

WILLIAM A. HILLER.
